UNITED STATES PATENT OFFICE.

JOSEPH J. BODEK, OF PHILADELPHIA, PENNSYLVANIA.

COLLAR-BAND FOR SHIRTS.

1,101,991.

Specification of Letters Patent. Patented June 30, 1914.

Application filed September 2, 1913. Serial No. 787,575.

To all whom it may concern:

Be it known that I, JOSEPH J. BODEK, a citizen of the United States, residing at Philadelphia, in the county of Philadelphia and State of Pennsylvania, have invented certain new and useful Improvements in Collar-Bands for Shirts, of which the following is a specification.

My invention relates to improvements in collar bands for shirts, the object of the invention being to provide a shirt at the collar with integral attaching devices which dispense with the necessity for independent buttons to connect the ends of the collar band and to attach the ordinary collar to the shirt.

A further object is to provide a garment with attaching members of the same material as the garment, and which form an integral part of the garment.

A further object is to provide an improved construction of collar band which may be readily attached to any ordinary shirt and which contains its own attaching devices.

With these and other objects in view, the invention consists in certain novel features of construction and combinations and arrangements of parts as will be more fully 30 hereinafter described and pointed out in the claim.

In the accompanying drawings: Figure 1 is a fragmentary perspective view illustrating my improved collar band on a shirt. Fig. 2 is a view illustrating a blank constituting one half of my improved collar band, and Fig. 3 is a view in vertical section on an enlarged scale through the collar band on the line 3—3 of Fig. 1.

1 represents a shirt and 2 my improved collar band which is composed of two pieces 3, 3. One of these pieces is shown in Fig. 2 and is flat in the form of a blank. Both pieces are precisely alike and are of the material of which the band is made, such for example as linen or other woven fabric. The piece 3 is folded on a center longitudinal fold line 4 and is also folded on lines 5 adjacent its edges. In other words, the edges of the piece 3 are turned in after the piece is folded on the line 4, and when the two pieces 3, 3, are together, the inwardly turned edges give to the collar band at its outer edge, an eight-ply thickness as seen clearly in Fig. 3, which thickness is se-

cured by lines of stitching 6. The pieces 3, 3, at their lower edges are located at opposite faces of the shirt and sewed to the shirt by a line of stitching 7. One end of the collar band formed by the pieces 3, 3, is 60 extended beyond the edge of the shirt and cut out forming a locking tongue 8, and the lines of stitching throughout the collar band extend throughout the edge of this locking tongue to securely hold the several thicknesses of material together. The other end of the collar band is provided with an opening 9 through which the tongue 8 is projected, and a second tongue 8^a is stamped from the band and is adapted to be projected through the front button holes of any ordinary collar and secure the collar to the collar band. At the rear of the collar band, a similar tongue 10 is formed by stamping the several thicknesses of the collar band or in other words, forming a cut 75 in the collar band which when forced outwardly will provide a tongue similar to the tongue 8, and this tongue 10 is designed to be projected through the rear button hole of 80 an ordinary collar.

By constructing a collar band of several thicknesses of material, the tongues 8 and 10 may be given the desired rigidity to operate as effective attaching means, and may be 85 manipulated by the fingers to fasten and unfasten as desired.

While I have described my invention in connection with a collar band, I would have it understood that it is capable of other uses, 90 and I do not limit myself to the particular use nor to the details of construction set forth, but consider myself at liberty to make such changes and alterations as fairly fall within the spirit and scope of the appended 95 claim.

Having thus described my invention, what I claim as new and desire to secure by Letters Patent is:

A collar band of the character described, 100 comprising two pieces, each piece folded longitudinally and having its edges bent inwardly with lines of stitching extending through the eight thicknesses of material thus formed at the outer edge of the band, 105 said pieces at their folded edges adapted to be secured to the inner and outer faces of a shirt at the neck, said collar band at one end having a tongue projecting beyond the edge of the shirt and at its other end having an 110

opening to receive the tongue, and said collar band adjacent the first-mentioned tongue and midway between the ends of the band having integral tongues cut from the band between its upper and lower edges, and bent outwardly from the band for attachment to a collar, substantially as described.

In testimony whereof I have signed my name to this specification in the presence of two subscribing witnesses.

JOSEPH J. BODEK.
